UNITED STATES PATENT OFFICE.

DAVID FRANK, OF BROOKLYN, NEW YORK, ASSIGNOR OF ONE-HALF TO
JOHN TROUNSTINE, OF NEW YORK, N. Y.

DESIGN FOR AN END FRAME FOR METAL BEDSTEADS.

SPECIFICATION forming part of Design No. 27,508, dated August 10, 1897.

Application filed July 3, 1897. Serial No. 643,457. Term of patent 7 years.

To all whom it may concern:

Be it known that I, DAVID FRANK, a citizen of the United States, residing at Brooklyn, in the county of Kings and State of New York, 5 have invented and produced a new and original Design for the End Frame of a Metal Bedstead; and I do declare the following to be a full, clear, and exact description of the same, reference being had to the accompanying 10 drawing, forming a part thereof, in which is illustrated a front elevation of the head end frame of a metal bedstead embodying my design, the side rails of the bedstead being in section.

15 The leading feature of my design consists in the ornamental outlines described by the metal rods which compose the main body of the frame intermediate the vertical corner-posts and the upper and lower horizontal rails, substantially as shown in the accompanying 20 drawing.

In the drawing, A A designate the vertical corner-posts, and B B the usual upper and lower rails. The posts A A and rails B B outline a space C, within the center of which is 25 the ornamental rod-frame D, comprising the four members E F G H. The members E F at the ornamental boxes I J join the upper and lower horizontal rails B B, and the members G H at the ornamental boxes K L join 30 side rails M.

What I claim is—

The design for the end frame of a metal bedstead, substantially as shown and described.

35 In testimony whereof I affix my signature in presence of two witnesses.

DAVID FRANK.
